UNITED STATES PATENT OFFICE.

JAMES ROBERTSON WHITE, OF SCHENECTADY, NEW YORK.

RADIATOR.

1,194,909.

Specification of Letters Patent. Patented Aug. 15, 1916.

Application filed April 14, 1914. Serial No. 831,853.

To all whom it may concern:

Be it known that I, JAMES R. WHITE, a citizen of the United States, residing at Schenectady, in the county of Schenectady 5 and State of New York, have invented new and useful Improvements in Radiators, of which the following is a specification.

The invention relates to radiators designed for use in connection with automobiles or 10 the like, and is particularly directed to a structure in which the parts are so arranged as to force circulation of air around the tubes, while at the same time permitting convenient and easy repair.

15 The main object of the present invention is the provision of a radiator in which tubes are made up of solder sections, each tube being of sinuous formation longitudinally and adjacent the tubes disposed relatively 20 offset so as to provide an air passage to force the maximum quantity of air to and around the tubes.

The invention in the preferred form of 25 details will be described in the following specification, reference being had particularly to the accompanying drawings, in which:—

Figure 1 is a front elevation of the improved radiator. Fig. 2 is a vertical section on the line 2—2 of Fig. 1. Fig. 3 is a 30 perspective view of one of the tubes. Fig. 4 is a transverse section of the same.

The improved radiator as shown in the accompanying drawings, comprises a casing 1 having a central opening space 2 above and 35 below which are arranged water chambers 3 and 4. These chambers are provided with suitable inlets and outlets 5 and 6.

The tubes 7 are constructed of sections 8 and 9, which are soldered together to form 40 a rectangular tube, each tube throughout its length being of sinuous formation with the respective portions thereof angularly related. This disposition of the tubes provides air space between the same. The adja-

cent tubes are reversely arranged with respect to their sinuous disposition and the crossing or meeting portions are soldered together to insure a comparatively rigid structure.

The ends of the tubes connect with the 45 respective water chambers so as to provide the necessary circulation, the plates forming the bottom and top of the respective chambers being formed with openings in which the ends of the tubes are secured in appropriate manner.

The front and rear gradings 10 and 11 are 50 secured to the casing, the latter being provided with a movable securing means for the grading of any appropriate type.

In the arrangement described, it is apparent that the sinuously formed tube will contain more water than the usual straight tube and hence by reason of the greater surface presented to the air will result in the greater 55 cooling of the water in the same time. Furthermore, any one or more tubes may be easily removed when repair is necessary, or when it is desired to replace the tube by a new one, by removing the radiator or correct 60 a leak without interfering with any other connections.

What is claimed is:—

In combination a radiator, a series of sinuous tubes having their opposite ends secured 65 at the opposite sides of the radiator, each of said sinuous tubes being composed of a series of similarly sized and similarly shaped sections, each section consisting substantially of an oblong body hollowed out and formed 80 with an opposite end with edges beveled in the same direction.

In testimony whereof, I affix my signature in presence of two witnesses.

JAMES ROBERTSON WHITE.
